US00D484031S

(12) **United States Design Patent** (10) Patent No.: **US D484,031 S**
 Ellis et al. (45) Date of Patent: ** Dec. 23, 2003

(54) **CAPTIVE SCREW**

(75) Inventors: **Thomas J. Ellis**, Wilmington, DE (US); **Edward A. McCormack**, Chadds Ford, DE (US); **Harry L. Dickerson**, Downingtown, PA (US); **William R. Frame**, Brookhaven, PA (US); **Steven M. Lubeck**, Aldan, PA (US)

(73) Assignee: **Southco, Inc.**, Concordville, PA (US)

(**) Term: **14 Years**

(21) Appl. No.: **29/170,528**

(22) Filed: **Nov. 7, 2002**

CLAIM

The ornamental design for a captive screw, as shown and described.

DESCRIPTION

FIG. 1 is a side elevation of a captive screw showing our new design, all remaining sides being identical;

FIG. 2 is a perspective view thereof;

FIG. 3 is a bottom plan view thereof;

FIG. 4 is a top plan view thereof showing a six lobed driver recess;

FIG. 5 is an alternate top plan view thereof showing a combined six lobed/slotted driver recess;

FIG. 6 is an alternate top plan view thereof showing a slotted driver recess;

FIG. 7 is an alternate top plan view thereof showing a Phillips driver recess;

FIG. 8 is an alternate top plan view thereof showing a combined slotted/Phillips driver recess;

FIG. 9 is a side elevation of a captive screw showing a second embodiment of our new design, all remaining sides being identical;

FIG. 10 is a perspective view thereof;

FIG. 11 is a bottom plan view thereof;

FIG. 12 is a top plan view thereof showing a six lobed driver recess;

FIG. 13 is an alternate top plan view thereof showing a combined six lobed/slotted driver recess;

FIG. 14 is an alternate top plan view thereof showing a slotted driver recess;

FIG. 15 is an alternate top plan view thereof showing a Phillips driver recess;

FIG. 16 is an alternate top plan view thereof showing a combined slotted/Phillips driver recess;

FIG. 17 is a side elevation of a captive screw showing a third embodiment of our new design, all remaining sides being identical;

FIG. 18 is a perspective view thereof;

FIG. 19 is a bottom plan view thereof;

FIG. 20 is a top plan view thereof showing a six lobed driver recess;

FIG. 21 is an alternate top plan view thereof showing a combined six lobed/slotted driver recess;

FIG. 22 is an alternate top plan view thereof showing a slotted driver recess;

FIG. 23 is an alternate top plan view thereof showing a Phillips driver recess;

FIG. 24 is an alternate top plan view thereof showing a combined slotted/Phillips driver recess;

FIG. 25 is a side elevation of a captive screw showing a fourth embodiment of our new design, all remaining sides being identical;

FIG. 26 is a perspective view thereof;

FIG. 27 is a bottom plan view thereof;

FIG. 28 is a top plan view thereof showing a six lobed driver recess;

FIG. 29 is an alternate top plan view thereof showing a combined six lobed/slotted driver recess;

FIG. 30 is an alternate top plan view thereof showing a slotted driver recess;

FIG. 31 is an alternate top plan view thereof showing a Phillips driver recess;

FIG. 32 is an alternate top plan view thereof showing a combined slotted/Phillips driver recess;

FIG. 33 is a side elevation of a captive screw showing a fifth embodiment of our new design, all remaining sides being identical;

FIG. 34 is a perspective view thereof;

FIG. 35 is a bottom plan view thereof;

FIG. 36 is a top plan view thereof showing a six lobed driver recess;

FIG. 37 is an alternate top plan view thereof showing a combined six lobed/slotted driver recess;

- FIG. 38 is an alternate top plan view thereof showing a slotted driver recess;
- FIG. 39 is an alternate top plan view thereof showing a Phillips driver recess;
- FIG. 40 is an alternate top plan view thereof showing a combined slotted/Phillips driver recess;
- FIG. 41 is a side elevation of a captive screw showing a sixth embodiment of our new design, all remaining sides being identical;
- FIG. 42 is a perspective view thereof;
- FIG. 43 is a bottom plan view thereof;
- FIG. 44 is a top plan view thereof showing a six lobed driver recess;
- FIG. 45 is an alternate top plan view thereof showing a combined six lobed/slotted driver recess;
- FIG. 46 is an alternate top plan view thereof showing a slotted driver recess;
- FIG. 47 is an alternate top plan view thereof showing a Phillips driver recess;
- FIG. 48 is an alternate top plan view thereof showing a combined slotted/Phillips driver recess;
- FIG. 49 is a side elevational view of the captive screw showing a seventh embodiment of our new design, the remaining views appearing the same as those of the sixth embodiment;
- FIG. 50 is a side elevation of a captive screw showing an eighth embodiment of our new design, all remaining sides being identical;
- FIG. 51 is a perspective view thereof;
- FIG. 52 is a bottom plan view thereof;
- FIG. 53 is a top plan view thereof showing a six lobed driver recess;
- FIG. 54 is an alternate top plan view thereof showing a combined six lobed/slotted driver recess;
- FIG. 55 is an alternate top plan view thereof showing a slotted driver recess;
- FIG. 56 is an alternate top plan view thereof showing a Phillips driver recess;
- FIG. 57 is an alternate top plan view thereof showing a combined slotted/Phillips driver recess;
- FIG. 58 is a side elevational view of the captive screw showing a ninth embodiment of our new design, the remaining views appearing the same as those of the eighth embodiment;
- FIG. 59 is a side elevation of a captive screw showing a tenth embodiment of our new design, all remaining sides being identical;
- FIG. 60 is a perspective view thereof;
- FIG. 61 is a bottom plan view thereof;
- FIG. 62 is a top plan view thereof showing a six lobed driver recess;
- FIG. 63 is an alternate top plan view thereof showing a combined six lobed/slotted driver recess;
- FIG. 64 is an alternate top plan view thereof showing a slotted driver recess;
- FIG. 65 is an alternate top plan view thereof showing a Phillips driver recess;
- FIG. 66 is an alternate top plan view thereof showing a combined slotted/Phillips driver recess;
- FIG. 67 is a side elevational view of the captive screw showing an eleventh embodiment of our new design, the remaining views appearing the same as those of the tenth embodiment;
- FIG. 68 is a side elevation of a captive screw showing a twelfth embodiment of our new design, all remaining sides being identical;
- FIG. 69 is a perspective view thereof;
- FIG. 70 is a bottom plan view thereof;
- FIG. 71 is a top plan view thereof showing a six lobed driver recess;
- FIG. 72 is an alternate top plan view thereof showing a combined six lobed/slotted driver recess;
- FIG. 73 is an alternate top plan view thereof showing a slotted driver recess;
- FIG. 74 is an alternate top plan view thereof showing a Phillips driver recess;
- FIG. 75 is an alternate top plan view thereof showing a combined slotted/Phillips driver recess; and,
- FIG. 76 is a side elevational view of the captive screw showing a thirteenth embodiment of our new design, the remaining views appearing the same as those of the twelfth embodiment.
- It is understood that for each alternate top plan view in each embodiment in the drawings, the bottom plan, perspective and side elevations are identical to those shown.
